UNITED STATES PATENT OFFICE.

JAMES M. HARTLEY, OF WASHINGTON, DISTRICT OF COLUMBIA.

HAIR-PIN.

No. 812,741.

Specification of Letters Patent.

Patented Feb. 13, 1906.

Application filed October 27, 1905. Serial No. 284,687.

To all whom it may concern:

Be it known that I, JAMES M. HARTLEY, a citizen of the United States, residing at Washington, in the District of Columbia, have invented new and useful Improvements in Hair-Pins, of which the following is a specification.

This invention relates to improvements in hair-pins provided with a device designed to prevent the pin from becoming disengaged from the hair and falling out.

The prime object of the invention is to provide a locking device situated so that when the pin is inserted the lock will be opened to permit its free passage into the hair, and when it has been properly positioned and the hand is removed a spring normally closes the lock against the pin and prevents the latter falling from the hair.

Other objects and advantages will be hereinafter described, and particularly pointed out in the claims.

In the drawings, Figure 1 is a perspective view of my improvement, showing it in position to be inserted in the hair. Fig. 2 is a similar view showing the lock closed. Fig. 3 is a transverse section on the line $x-x$, Fig. 2.

1 indicates a hair-pin of usual construction composed of the two prongs 2 2 and connecting-bar 3. On the inside of one of the prongs 30 is formed a seat 4, which receives a tongue of a lock, while the cross-bar is provided with a projection 5, formed with an opening 6.

Straddling the cross-bar 3 is a finger-piece 7 of a lock member. A pin 8, passing through openings in the finger-piece and opening 6 in the projection, serves as a pivot for the lock. Depending from one side of the finger-piece is the lock member 9, the lower end of which is twisted to lie between and parallel with the prongs 2 2, the lower end engaging the seat 4. A spring 10 encircles the pin, one end of which engages the under side of the finger-piece, while the opposite end engages under the cross-bar 3.

45 In placing a hair-pin the prongs are usually held between three fingers and the thumb, and the forefinger engages the cross-

bar 3 to force it in position. When the pin is forced in the hair by the forefinger, pressure is applied at the point marked *a*, which 50 turns the finger-piece on its pivot and disengages the lock from its seat, which permits said lock to pass freely through the hair without catching into the latter. When the pin has been properly located and the fingers 55 are removed, the spring returns the lock to normal position. As previously stated, the end of the lock normally rests in the seat. Consequently when the lock closes after the pin has been inserted in position strands of 60 hair will be held in the space *b* between the lock and the prong, which effectually prevents the pin from becoming loose.

By pivoting the lock to the cross-bar as described I accomplish the highly-important 65 function of opening it by the same operation of inserting the pin in the hair, thus dispensing with the necessity of using both hands in applying a hair-pin provided with my improvement.

70 What I claim is—

1. In combination, a hair-pin having prongs and a connecting-bar, a seat formed on the inside of one of the prongs, a finger-piece straddling the connecting-bar and pivotally 75 mounted thereon, a locking device depending from the finger-piece between the prongs, the end of the locking device engaging the seat, and a spring for holding the locking device in the seat.

2. In combination, a hair-pin having prongs and a cross-bar, a seat formed in one of the prongs, a pivoted locking device mounted on the cross-bar and extending between the prongs and twisted to make its lower end 85 parallel with the prongs to engage the seat, and a spring to retain the lock in its seat.

In testimony whereof I affix my signature in presence of two subscribing witnesses.

JAMES M. HARTLEY.
